UNITED STATES PATENT OFFICE.

CHARLES W. MUNZ, OF DETROIT, MICHIGAN.

MACHINE FOR GRAINING WOOD.

No. 846,131.

Specification of Letters Patent.

Patented March 5, 1907.

Application filed May 20, 1905. Serial No. 261,450.

To all whom it may concern:

Be it known that I, CHARLES W. MUNZ, residing at Detroit, in the county of Wayne and State of Michigan, a citizen of the United States, have invented certain new and useful Improvements in Machines for Graining Wood, of which the following is a specification, reference being had therein to the accompanying drawings.

10 The invention relates to machines designed for transferring to a surface an impression or exact reprint of the natural grain of wood.

15 It is the more specific object of the invention to obtain a machine adapted for graining boards or fashioned surfaces of a common wood to produce the appearance of a higher grade of material. Thus, for example, articles formed from maple may be given 20 the appearance of quartered oak, or, if desired, a soft wood may be given the appearance of hard wood. It is obvious that for many uses the softer or cheaper grades of wood are equal or superior to more expensive varieties in everything but appearance, 25 and by the use of my invention the latter also is obtained.

In the drawings, Figure 1 is a vertical longitudinal section through the machine. Fig. 3 is an enlarged sectional perspective view of the scraper for cleaning the wood pattern. Fig. 3 is a plan view thereof. Fig. 4 is an elevation illustrating the machine as adapted for graining a fashioned surface.

35 My invention is of that type in which the patterned surface is upon a revolving cylinder and the grain of the pattern is preferably arranged to extend circumferentially thereof.

As shown, A is a suitable framework in 40 which is journaled a shaft B, having mounted thereon the drum or cylinder C. This cylinder, as illustrated, is formed by a plurality of metallic heads *a*, secured to the shaft, upon which are a series of staves *b*, and the 45 patterned surface *c* is secured to these staves.

D is a transfer-roller which is journaled in vertically-adjustable bearings, preferably in the pivotal links E, secured to opposite ends of the frame. These links are adjusted by 50 means of a screw F, so as to move the transfer-roll in or out of contact with the cylinder or to vary the tension with which it is placed into contact with the patterned surface.

55 G is a tank or vat into which the lower portion of the cylinder C dips and which contains

the pigment which fills the grain of the wood pattern and is transferred to the roller D.

Constructions substantially as above described have heretofore been employed in graining-machines, and the present invention relates to certain improvements which render the operation more perfect and adapt the machine for a greater range of work. The first of these improvements is the construction of a scraper by which the surplus pigment is removed from the patterned surface before the transfer of the impression to the roller D. It is very essential that all portions of the surface with the exception of the grain indentations should be thoroughly cleaned from the pigment, as otherwise a smearing or discoloration is produced in the print. This cleaning is difficult for the reason that the patterned surface is never a true cylinder and under the influence of a liquid 75 pigment often is swelled considerably out of form. Thus any rigid or semi-rigid scraper will not clean all portions alike. In my construction I employ a scraping edge which is formed of a material of a flexible nature, 80 such as leather, and the necessary pressure upon the surface is produced by a resilient reinforcement. Furthermore, the resilient member is so formed that the tension on various portions of the scraping edge may be 85 adjusted when necessary, so as to produce a uniform effect throughout its entire length.

As illustrated, H is the scraping edge, which is formed of a flat strip of leather and is clamped between a number of supporting-bars I I'. One of these bars is adjustably secured to the frame of the machine, as by the trunnions *d* at opposite ends, which engage with slots *e* in the side frames and are adjusted laterally by the thumb-screws *f*. 90 The angularity of the bars I to the scraper H may be changed by means of rock-arms *g*, engaging with a laterally-adjustable bearing *h*, operated by the adjusting-screw *i*. The bars I I' are clamped together by bolts *J*, preferably having wing-nuts *J'*, by means of which the scraper H is quickly clamped or released. The scraper is also adjusted in relation to the clamping-bars I I', and for this purpose a metallic bar *j* is placed in rear of the leather strip and is adjusted by a series of thumb-screws *k*. The resilient reinforcement for the scraper is formed by a series of springs *K*, which are attached to the clamping-bar I' and project forward therefrom into contact 110

with the upper face of the leather scraper H. Each of these springs may be adjusted in tension by a thumb-screw L, which engages a threaded bearing in the bar M, secured to the 5 bars I I' by the bolts J.

With the construction just described the scraper H may be adjusted by the thumb-screws k to have all portions of its scraping edge equidistant from the pattern-cylinder.

10 By the adjusting-screws f the scraper can be moved toward or from the cylinder, and by the adjusting-screw i its angularity may be changed. Finally, by the adjusting-screw L the tension of the various springs K may be 15 adjusted so as to place the required tension on each portion of the scraping edge to hold it in contact with the patterned surface. The result is that the surface is cleanly wiped by the scraper and produces a clear expression 20 upon the transfer-roll, which is subsequently printed on the surface to be grained.

The pigment which is placed in the grain of the pattern is held in the tank G, before described. This tank is preferably vertically 25 movable from the position shown in full lines to that indicated in dotted lines and to this end is supported by the parallel links N N' and is raised and lowered by the crank-arm O. This crank-arm engages a slotted bearing P at the bottom of the tank, and by 30 swinging the crank a quarter-turn the adjustment is effected. In the lower position of the tank it is also thrown forward, so that it can be conveniently filled or cleaned.

35 Where the machine is used for graining flat boards, I preferably provide a supporting-roll Q, which is journaled in detachable standards R upon the frame A. This roll is on a level with the transfer-roll D and serves to 40 support the board while it is fed over the transfer-roll to receive the impression therefrom. For holding the board in contact with the transfer-roll and also to assist in feeding it an adjustable presser-roll S is employed, 45 which is arranged above the transfer-roll, and this is preferably driven at the same peripheral speed as the transfer-roll, thereby feeding the board at a like speed. For driving the roll S, I preferably provide a belt connection S', 50 which connects pulleys respectively the same in diameter as the drum C and the roll S, and to provide for taking and giving slack for different adjustments of the roll S an idler-pulley T is adjustably secured to the frame 55 and bears against the belt S'. The roll S is preferably adjusted vertically by means of sliding bearings U, engaging the guide-frames U' at opposite ends of the frame and having connected thereto the threaded rods V. 60 These rods are connected to a common drive-shaft V' by the miter-gears V², and thus the operator by rotating the shaft V' may raise or lower the roll S for different thicknesses of work.

65 Where the machine is used for fashioned

surfaces, the work is pressed into the elastic surface of the transfer-roll D, so as to contact with all portions of the surface. If the work is of such shape that the feed-roll S cannot be used, the latter may be turned out of the way 70 by swinging downward the frames U', which are pivotally connected with the frame A and are normally clamped thereto.

The machine is frequently used for graining boards or other surfaces which are of 75 lesser width than the pattern-roll. As a consequence it is necessary to remove all of the pigment remaining upon the transfer-roll D after it has contacted with the surface to be grained, and to this end a scraper W is arranged as shown. This scraper is preferably 80 formed of a metallic straight-edge m, secured to a bar n, which is detachably secured in slotted bearings in the frame by means of the thumb-screws o. The scraper is preferably 85 adjusted so as to bear against the surface of the transfer-roll D, and before the latter has completed a revolution from the point of receiving the impression the pigment will be scraped off by the metallic straight-edge m. 90

What I claim as my invention is—

1. In a graining-machine, the combination with a traveling wood-pattern surface, of a scraper for removing the surplus pigment therefrom comprising a leather strip forming 95 a scraping edge, and a metallic spring-strip for yieldingly pressing said leather against the pattern-surface.

2. In a graining-machine, the combination with a traveling wood-pattern surface, of a 100 scraper for removing the surplus pigment therefrom consisting of a continuous leather strip forming the scraping edge, a series of metallic springs backing said scraping edge and individual tension adjustments for each 105 spring.

3. In a graining-machine, the combination with a traveling wood-pattern surface, of a scraper for removing the surplus pigment therefrom consisting of a pair of clamping- 110 bars, a leather strip arranged between the same and projecting to form a scraping edge for bearing against the pattern-surface, and screws bearing against the rear edge of said leather strip for adjusting the same toward 115 the pattern-surface at different points in the length thereof.

4. In a graining-machine, the combination with a traveling wood-pattern surface, of a scraper for removing the surplus pigment 120 therefrom consisting in a leather strip and a pair of clamping-bars embracing the same, means for adjusting said bars in angularity and in distance from the pattern-surface, a series of springs for backing the leather strip, and individual adjusting-screws for varying 125 the tension of said springs.

5. In a graining-machine, the combination with a rotary wood pattern, of a segmental pigment-tank, and means for vertically ad- 130

justing said tank comprising a pair of link-hangers, a crank, and a slotted bearing supporting the tank with which said crank engages, whereby the tank may be simultaneously adjusted vertically and laterally.

6. In a graining-machine, the combination with a traveling wood-pattern surface, of a scraper for removing the surplus pigment therefrom, means for adjusting the scraper 10 toward or from said surface and means for moving portions of the scraping edge toward or from said surface.

7. In a graining-machine, the combination with a traveling wood-pattern surface, of a 15 scraper for removing the surplus pigment therefrom yieldingly pressed thereagainst, means for adjusting the tension of said scraper at different points in its length, and means for adjusting the angularity of said 20 scraper in relation to said surface.

8. In a graining-machine, the combination with a traveling wood-pattern surface, of a scraper having a flexible edge conformable to variations in the contour of said wood sur-

face, and auxiliary resilient means for pressing 25 the scraping edge in contact with the surface of the wood at all points in the length thereof.

9. In a graining-machine, the combination with a traveling wood-pattern surface, 30 of a scraper extending across said surface transversely of the direction of movement thereof, independently-adjustable reinforcements for said scraper and means for adjusting said scraper toward or from said surface. 35

10. In a graining-machine, the combination with a traveling wood-pattern surface, of a scraper extending across said surface, means for independently yieldingly pressing portions of the edge of said scraper against said 40 surface, and means for changing the angularity of said scraper to said surface.

In testimony whereof I affix my signature in presence of two witnesses.

CHARLES W. MUNZ.
